UNITED STATES PATENT OFFICE.

MICHAEL J. McGOWAN, JR., OF NEWARK, NEW JERSEY.

OUTLET-BOX.

No. 838,886.

Specification of Letters Patent.

Patented Dec. 18, 1906.

Application filed December 14, 1905. Serial No. 291,663.

To all whom it may concern:

Be it known that I, MICHAEL J. McGOWAN, Jr., a citizen of the United States, residing in the city of Newark, State of New Jersey, have 5 invented a new and useful Improvement in Outlet-Boxes, of which the following is a description.

Hitherto in boxes of the several types illustrated in the annexed drawings it has been 10 the custom to form the box and thimbles as separate pieces and after drawing the circuit-wires through the aperture formed in the box to secure the thimbles to the ends of said wires, after which the wires are drawn back 15 through the said apertures until the thimbles engage the interior of the box, and then the thimbles are secured to the box by some fastening means. By my construction I avoid this unnecessary labor both in manufacture 20 and in setting up by making the box and thimbles integral either by casting or by striking up from sheet metal by means of dies.

Another feature of my invention resides in 25 constructing the boxes with the thimbles projecting diagonally into the box. This is to avoid the making of too deep a cavity into 30 the wall or ceiling to receive the box. It frequently happens in electrical wiring that these boxes are required to be set into the 35 walls where the plastering is backed up by a brick wall, and the depth of the box is such that the insertion of the wires into apertures in the bottom of the boxes is impracticable without cutting a deep cavity in the wall to 40 make room for the passing in of the wires.

In the accompanying drawings, forming a 45 part of this specification, Figure 1 is a sectional view of my improvement as applied to an oblong switch-box. Fig. 2 is a plan view of the same. Fig. 3 is a sectional view of a square wall-box. Fig. 4 is a plan view, and Fig. 5 is a sectional view, of a circular ceiling-box. Figs. 6 and 7 are plan and sectional views of a circular ceiling-box provided with 50 diagonal thimbles.

In Figs. 1 and 2 I illustrate a switch or receptacle box in which A is the box-body, provided on its open side with the laterally-projecting flanges a, having the screw or bolt 55 holes a'. Projecting into the cavity of the

box are the integral thimbles B, having the cylindrical cavities b and contracted apertures b'. The set-screws C are provided for securing the ends of the circuit-wires in position in the cavities b with their stripped portion projecting through the apertures b'. 55

In Figs. 4 and 5 I show a ceiling-box A', of circular form, with the thimbles B' projecting into the cavity of the box parallel with the axis thereof, as shown. D is a central 60 aperture in the bottom of the box for the passage of a gas-pipe where the box is used in connection with a gas-lighting system.

In Figs. 6 and 7 I show the thimbles B² as extending diagonally into the box for the 65 purpose hereinbefore described.

It will thus be seen that by beveling the lower corners of the box, as illustrated in Figs. 1, 2, and 3, and the lower periphery of the circular box, as illustrated in Figs. 6 and 7, I am enabled to insert the circuit-wires without excessive excavation to the rear of the box, while the making of the thimbles integral with the box avoids much labor in wiring up and produces a box of neat and 75 efficient construction.

What I claim is—

1. An outlet-box for electric wiring having thimbles integral therewith, said thimbles projecting into the cavity of the box. 80

2. An outlet-box for electric wiring having thimbles integral therewith, said thimbles projecting diagonally into the cavity of the box.

3. An outlet-box for electric wiring having 85 the lower edge thereof beveled and an integral thimble projecting diagonally into the box from said beveled edge.

4. An outlet-box for electric wiring provided with integral thimbles, a contracted 90 aperture in the bottom of each of said thimbles for the introduction of circuit-wires, and means for securing said wires in position.

This specification signed and witnessed this 8th day of December, 1905.

MICHAEL J. McGOWAN, JR.
